W. A. SMITH.

PIN PULLER.

APPLICATION FILED SEPT. 16, 1918. RENEWED MAR. 8, 1920.

1,337,670.

Patented Apr. 20, 1920.

UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

PIN-PULLER.

1,337,670.

Specification of Letters Patent. Patented Apr. 20, 1920.

Application filed September 16, 1918, Serial No. 254,317. Renewed March 8, 1920. Serial No. 364,243.

To all whom it may concern:

Be it known that I, WILLIAM A. SMITH, a citizen of the United States, residing at Easton, in the county of Northampton and 5 State of Pennsylvania, have invented a certain new and useful Improvement in Pin-Pullers, of which the following is a specification.

This invention relates to pin pullers and 10 has reference particularly to a pin puller adapted to be mounted on a drill sharpener for the purpose of withdrawing a pin from the steel after it has been used in the operation of forging the lugs on the drill steel.

15 The objects of the present invention are to provide a pin puller which may be readily mounted upon the side of a drill sharpener and which may be utilized to withdraw the pin from the drill steel as quickly as 20 possible; also, to provide a pin puller which will be simple, readily operated, and not easily put out of order.

During the process of formation of lugs or collars usually found near the tool end of 25 rock drill steels in steels which are provided with a central hole extending throughout their length, a pin is placed in the end of this central hole extending a short distance within the hole in order to prevent its becoming closed or clogged during the forging and shaping of the lugs or collars. During 30 this operation the pin becomes firmly wedged in the hole and some form of pulling device, in which considerable force can 35 be exerted, is necessary to withdraw it.

The pulling means for the pin should properly be handily mounted in close proximity to the sharpening machine in order to withdraw the pin before the drill steel has 40 become cooled to such a degree as to render the pulling possible without reheating. The present construction has been devised to provide such a puller fulfilling these requirements and having these objects, a more 45 detailed description of which will follow.

With the above and other objects in view, therefore, the present invention consists in the features of construction and operation disclosed in the following specification and 50 illustrated on the accompanying drawings, forming a part hereof, in which—

Figure 1 shows, in perspective, a pin puller mounted on the side of a drill sharpener shown in outline; and

55 Fig. 2, a drill steel with pin inserted before the lugs or collars have been formed.

Referring more particularly to the drawing, 1 refers to the base or body member adapted to be secured to the side of a drill sharpener by means of cap screws 2. At 60 the upper portion of this base member are projections 3 each provided with a hole 3^a extending longitudinally of the base member 1. Above the forward projection 3 extend short arms 4 providing a bearing for 65 a short cross shaft 5 having a cam 6 rigidly fastened thereto. The top portion of the forward projection 3 is slightly concaved as shown at 7 so that a small bearing is provided for the pin 8. Sliding within the 70 holes 3^a provided in projections 3 is a member 9 having at its forward end an abutment 10 against which the drill 11 may rest and also provided with an orifice 12 through which the pin 8 may pass. At the rear end 75 of the member 9 a bifurcated portion 13 is formed having a pin 14 extending between the bifurcations engaging a slot 15 provided in a bell crank lever 16 which may oscillate about a pivot 17 provided in an extension 18 of the base member 1.

Through a reach arm 19 the bell crank 16 is connected with a pedal lever 20 which may be suitably counterweighted by means of weight 21 so that movement downward 85 on the foot portion 22 of the lever 20 will advance the member 9 and abutment 10 forcing them away from the clamping means formed by the projection 3 and cam member 6.

In operation, the drill steel 11 with pin 8 inserted is pressed against the abutment 10, the pin 8 extending through orifice 12 sufficiently to be grasped between the depression 7 and cam member 6. The cam 6 is 95 pressed against the pin 8 by rotating the shaft 5 which may readily be done by means of the ball 15^a provided on this shaft. Pedal 22 is now pressed which has the effect of thrusting forward the abutment 10 and 100 with it the drill steel 11 thus partly removing the pin 8 from the drill steel. This operation may be repeated several times, or until the pin has been completely removed from the drill.

From the above it will be seen that a pin puller has been provided which may be conveniently mounted on the side of a drill sharpener, which is simple and rugged in construction and one that takes up but little 110 space and may be cheaply manufactured.

It is to be understood that the present

showing and description disclose only one specific embodiment of the present invention and that other forms and modifications are included within the spirit and scope of 5 the invention as expressed in the appended claims.

What I claim is:

1. In a pin puller for drill sharpeners, 10 and a movable member adapted to securely grasp a pin, a movable abutment against which a drill is adapted to rest and means engaging said abutment for moving it away from said clamping means.
- 15 2. In a pin puller for drill sharpeners,

clamping means comprising a stationary member and a movable cam member adapted to securely grasp a pin, an abutment mounted to slide toward and away from said clamping means and means for 20 operating said abutment whereby a drill resting against said abutment may be moved from said clamping means and a pin inserted within said drill withdrawn.

In testimony whereof, I have hereunto set 25 my hand.

WILLIAM A. SMITH.
